UNITED STATES PATENT OFFICE.

BYRON ELIJAH CAGLE AND MATTHEW LINCOLN CAGLE, OF MOUNTAINAIR, NEW MEXICO.

PUMPING-MACHINE.

1,190,218.

Specification of Letters Patent.

Patented July 4, 1916.

Application filed August 17, 1915. Serial No. 46,008.

To all whom it may concern:

Be it known that we, BYRON ELIJAH CAGLE and MATTHEW LINCOLN CAGLE, citizens of the United States, residing at Mountainair, in the county of Torrance and State of New Mexico, have invented a new and useful Pumping Machine, of which the following is a specification.

Our invention relates to improvements in rotary pumps, and the object of our invention is to use three forces conjunctively, namely, direct contact, centrifugal and suction force in the same machine in order to efficiently raise any given quantity of water. We attain this object by the mechanism illustrated in the accompanying drawing, in which—

Figure 1 is a view of the pump partly in section, and Fig. 2 of the drawing is a vertical view of the casing, the lower portion thereof being broken away. Fig. 3 is a horizontal section taken on line 3—3 of Fig. 1.

The pump is essentially an auger incased and rigidly secured in an air tight cylinder, and provided with an annular air tight conduit pipe to discharge the water as is illustrated by SS in Fig. 2 of the drawing.

In Fig. 1 the framework F is simply a support for the pump proper whereby it may be suspended over a creek or pond for pumping. The main shaft H is provided at the base with a pivotal bearing and is provided at the top with a suitable collar bearing B, and having a pulley P attached to said shaft for rotating the same. In Fig. 1 it is shown how the two first named forces are utilized, that is the direct contact force, which is secured by the helical blade (f Fig. 1) or flanges of the auger coming in contact with the water when the machine is set in motion, and the second or centrifugal force is secured by the high momentum of the machine whereby the water is thrown to the periphery and forced upward by the force of the water from below—the lower end of the casing C being left open to allow of the inward flow of the water.

The third and main force of suction is obtained by the annular conduit tube SS illustrated by the drawing. This conduit may be of any size and length so as to dispose of the water as fast as it reaches the top of the cylinder or casing C. The chief function of the conduit tube is to create suction and is made in circular or semi-circular form. This force of suction is brought about and caused by the unequal pressure of the atmosphere on the two extreme ends of the pump, the outlet or discharge port of the circular conduit tube SS when in operation revolving at a high speed, and away from the air pressure, and the intake or pressure of the air at the intake port being normal the water is caused to flow in the path of least resistance, which is to the discharge port of the annular conduit tube SS.

In carrying out the invention care must be taken always to harmonize the three forces by adjustment of the parts.

Wherefore what we claim and desire to secure by Letters Patent is.

A rotary pump comprising a cylinder closed at one end and open at the other end to provide a fluid inlet and having adjacent its closed end a peripheral port, a casing having a discharge port and rigidly connected to said cylinder adjacent its closed end and forming therewith an annular conduit which surrounds and is of less axial extent than said cylinder, and communicates at one end with said peripheral port and at its other end with said discharge port, a helical blade rigidly connected to said cylinder, and means for rotating said parts, whereby fluid is impelled through said cylinder and discharged centrifugally through said discharge port.
